UNITED STATES PATENT OFFICE.

ODIN G. CLAY, OF WASHINGTON, DISTRICT OF COLUMBIA.

WINDOW-CLEANER.

1,156,522.

Specification of Letters Patent.

Patented Oct. 12, 1915.

Application filed April 8, 1915. Serial No. 20,086.

To all whom it may concern:

Be it known that I, ODIN G. CLAY, a citizen of the United States, residing at Washington, in the District of Columbia, have 5 invented a new and useful Window-Cleaner, of which the following is a specification.

The device forming the subject matter of this application is adapted to be employed for removing frost, moisture and the like 10 from the window panes of vehicles.

One object of the present invention is to provide novel means for moving longitudinally of the window pane which is to be cleaned, a traveler which carries means for 15 cleaning the pane.

Another object of the invention is to provide novel means whereby a scraper carrier may be moved transversely of the plane defined by the window pane, as the traveler 20 on which the scraper carrier is mounted moves longitudinally of the pane.

Another object of the invention is to provide a combined means for moving the traveler and the scraper carrier longitudinally 25 of the pane and for advancing the scraper carrier toward the pane.

It is within the province of the disclosure to improve generally and to enhance the utility of devices of that type to which the 30 present invention appertains.

With the above and other objects in view which will appear as the description proceeds, the invention resides in the combination and arrangement of parts and in the 35 details of construction hereinafter described and claimed, it being understood that changes in the precise embodiment of the invention herein disclosed can be made within the scope of what is claimed, without de- 40 parting from the spirit of the invention.

In the accompanying drawings:—Figure 1 is an end elevation of a vehicle whereunto the device forming the subject matter of this application has been attached; Fig. 2 45 is a fragmental vertical section; Fig. 3 is a fragmental horizontal section; Fig. 4 is a rear elevation showing a portion of the traveler and parts carried thereby, certain elements being shown in section.

50 In the accompanying drawings the numeral 1 indicates a supporting structure, such as a car, provided with a sash frame 2 carrying a pane 3. Brackets 4 are attached to the car 1 above the window frame 2 and 55 in the brackets 4 is carried a spring actuated roller 5 which may be constructed like

an ordinary Hartshorn curtain roller, or in any other desired manner.

The invention comprises a traveler 6 in the form of a rod or bar mounted to move 60 vertically in a direction parallel to the sash frame 3. At its ends, the traveler 6 is equipped with transverse heads 7 carrying anti-friction means such as wheels 8, adapted to move in tracks 9 formed in the frame 65 work of the car 1. The upper ends of primary flexible elements 10 which may be tapes, are secured to the roller 5 and are wound about the roller. The depending ends of the flexible elements 10 are attached 70 to the traveler 6.

The invention comprises a scraper carrier 11 mounted to move vertically along with the traveler 6 and to move horizontally, that is, transversely of the window pane 3. The 75 scraper carrier which is denoted by the numeral 11, preferably is in the form of a bar and assembled therewith are supporting elements 12 which may be screws, the supporting elements 12 being slidably mounted 80 in the traveler 6 for horizontal movement. Compression springs 14 of considerable strength are interposed between the heads of the supporting elements 12 and the traveler 6. The carrier 11 is provided with 85 a pair of superposed scrapers 15 which may be resilient strips of rubber or other suitable material. The scrapers 15 are applied to the upper and lower edges of the carrier 11 and are held thereon by means of clips 16 90 in the form of strips, the clips 16 being retained on the carrier 11 by means of securing elements 17.

The invention comprises a pair of actuating members 18 in the form of wedges, each 95 comprising a head 19 and a shank 20, the forward and rear faces of the shanks 20 preferably being parallel. The actuating members or wedges 18 are mounted to move vertically in notches or seats 28 formed, as 100 shown best in Fig. 3, in the traveler 6, in the carrier 11 and in the uppermost securing strip 16. The actuating members 18 are provided with vertically elongated slots 29 whereby the actuating members are 105 mounted to slide on the supporting elements or screws 12.

Secondary flexible elements 21 are connected to the lower ends of the actuating members 18 and extend downwardly through 110 openings 22 in the window sill 25, around idlers 23, upwardly through openings 24

in the sill, across the roller 5, if desired, and rearwardly through openings 26 in the frame work of the car, the rear ends of the secondary flexible elements 21 being provided with handles 27 of any desired sort, in the present instance shown in the form of rings. As clearly shown in Fig. 2, the handles 27 abut against the frame work of the car to limit the movement of the traveler 6 in one direction, under the action of the spring driven roller 5.

In practical operation, the flexible elements 21 are drawn over the idlers 22 and move rearwardly at their upper ends, when 15 a pull is exerted on the handles 27. By this operation, the traveler 6 is caused to move downwardly, the flexible elements 10 being unreeled from the roller 5 and the springs thereof being put under tension. As the 20 traveler 6 is moved downwardly due to the pull exerted by the flexible elements 21 on the wedges 18, the wedges act transversely against the carrier 11 and move the same toward the window pane 3. Thus, the scrapers 15 are pressed firmly against the window 25 pane 3. So soon as the handles 27 are released, the spring driven roller 5 reacts on the flexible elements 10 and draws the traveler 6 upwardly. The springs 14 react 30 on the supporting elements 12 and pull the carrier 11 forwardly, and since the beveled heads 19 of the actuating members or wedges 18 are inclined, the actuating members will rise under the action of the springs 35 14 and assume again the positions of Fig. 2, the scrapers 15 thus being moved forwardly so that they coöperate with the forward face of the upper rail of the sash frame 2.

Having thus described the invention, what 40 is claimed is:

1. In a window cleaner, a traveler mounted to reciprocate in one plane; a scraper carrier mounted to reciprocate on the traveler toward and from scraping position at an 45 angle to the plane in which the traveler reciprocates; a wedge movably interposed between the carrier and the traveler and constituting means for advancing the carrier to scraping position when the wedge and

the traveler are moved in one direction; means assembled with the wedge for moving the wedge and the traveler in said direction; and means for moving the traveler in an opposite direction.

2. In a window cleaner, a traveler mounted to reciprocate in one plane; a scraper carrier mounted to reciprocate on the traveler toward and from scraping position at an angle to the plane in which the traveler reciprocates; a wedge movably interposed 55 between the carrier and the traveler and constituting means for advancing the carrier to scraping position when the wedge and the traveler are moved in one direction; means assembled with the wedge for moving the wedge and the traveler in said direction; means for moving the traveler in an opposite direction; and a resilient connection between the traveler and the carrier, whereby the traveler and the carrier will be 60 drawn together, thereby to move the wedge on the carrier and the traveler in the last specified direction.

3. In a window cleaner, a traveler mounted to reciprocate in one plane; a scraper carrier mounted to reciprocate on the traveler toward and away from scraping position at an angle to the plane in which the traveler reciprocates; a movable actuating element interposed between the carrier and the traveler and constituting means for advancing the carrier to scraping position when the actuating element and the traveler are moved in one direction; means assembled directly with the actuating element 75 for moving the actuating element independently of the traveler, the actuating element subsequently coacting with the traveler to move the same in said direction; and means for moving the traveler in an opposite direction.

In testimony that I claim the foregoing as my own, I have hereto affixed my signature in the presence of two witnesses.

ODIN G. CLAY.
